UNITED STATES PATENT OFFICE

WILLIAM S. HARLEY, OF MILWAUKEE, WISCONSIN

SPRING-SEAT POST.

979,483.

specification of Letters Patent. Patented Dec. 27, 1910.

Application filed April 30, 1910. Serial No. 558,598.

REISSUED

To all whom it may concern:

Be it known that I, WILLIAM S. HARLEY, a citizen of the United States, and resident of Milwaukee, in the county of Milwaukee 5 and State of Wisconsin, have invented certain new and useful Improvements in Spring-Seat Posts; and I do hereby declare that the following is a full, clear, and exact description thereof.

10 My invention has for its object to provide a resilient seat support for motorcycles, bicycles or like vehicles, the construction and arrangement being such that the required amount of resiliency is obtained, while at 15 the same time rigidity in a lateral direction is insured and back lash due to compression compensated for.

With these objects in view the invention consists in certain peculiarities of construction and combination of parts as set forth 20 hereinafter with reference to the accompanying drawings and subsequently claimed.

In the drawings Figure 1 represents an 25 elevation partly in section of a portion of a motorcycle frame provided with a seat support embodying the features of my invention; Fig. 2, a detail plan view of the hinge connection between the saddle supporting bar and vehicle frame; and Fig. 3, a partially sectional detail view of the shackle 30 connection, the section being taken at a right angle to Fig. 1.

Referring by characters to the drawings, 1 represents the top bar of a motorcycle frame, which bar is supplemented by a second bar 2 arranged parallel thereto, these bars being in brazed connection with a seat-mast 3. At a predetermined distance 35 from the seat-mast the top bar is bent and converges toward the lower bar forming an 40 oblique section 4, whereby the mouth of the seat-mast is lowered to a point below the axis of the upper bar in order that the seat, when placed in position, can be dropped to 45 a convenient point.

The mouth of the mast has brazed therein a gland 5, into which gland is fitted a tubular well that is preferably composed of two sections, the upper section 6 being provided 50 with a flanged end 7 that rests upon the outer end of the gland, said flange being clamped to the gland by means of a flanged coupling member that is in screw-threaded connection with a threaded shank of the 55 gland. The lower end of the upper well

section 6 has brazed or otherwise secured thereto a collar 8, having a screw-threaded extension for the reception of the correspondingly screw-threaded end of the lower tube section 9 of said well. This section of 60 the well is closed at its bottom to form a reservoir 10, which, as shown, may, in some instances, be partly filled with oil if desired.

A reciprocative sleeve post 11 is fitted into the upper section of the well as shown, being provided with a head 12, that is brazed or otherwise secured thereto, the head being provided with ears for the reception of a pin 13, upon which pin is loosely mounted a bearing-block 13^a. The head has secured 70 thereto a plunger-rod 14, which extends through the collar 8 that serves as a guide therefor and terminates adjacent to the bottom of the lower tube section with a piston-head 15. The piston-head is provided with 75 ports 15^a, which are controlled by a valve-disk 16, there being restricted vents 17 also extending through the disk head, which vents are constantly open while the ports are closed by the disk when the plunger-rod 80 rises.

Interposed between the upper face of the collar 8 and lower face of the head 12 is a coiled spring 18, which coiled spring surrounds the plunger and is adapted to support the load. A second coiled spring 19 is interposed between the lower face of the collar 8 and an adjustable nut and washer 20, the nut being in screw-threaded engagement with the plunger-rod 14, whereby tension of 90 the coiled spring 19 is adjusted simultaneously with adjustment of the upper spring 18.

The lower coiled spring 19 is provided for the purpose of cushioning the up-stroke of the seat-post incidental to sudden depression 95 thereof through shock, whereby shock to the rider is eliminated in either direction, it being understood that the adjusting nut 20 may be set in proportion to the weight of the rider, whereby the proper amount of resiliency is maintained.

Brazed or otherwise suitably secured to the top-bar 1 at the junction of the oblique portion 4 and horizontal portion 1 is a bracket 21, which bracket has extending 105 therefrom an apertured ear 22, for the reception of the crotched end 23 of a saddle-bar 24, the crotched end of the saddle-bar being provided with apertures through which a hinged pin 25 passes, the said hinged 110

pin being also passed through the aperture in the bracket ear.

Adjacent to the rear end of the saddle-bar there is secured a bracket having a depending slotted ear 26, into the slot of which ear the bearing-block 13^a is fitted, whereby the rear end of the saddle-bar is supported. By this shackle connection the seat-post and bar are connected and held rigid in a lateral direction while at the same time said connection will permit free downward movement of the seat-post within the mast due to play of the block 13^a within the slot of the ear 26, and, as shown in the drawing, the seat-post 15 is in its highest position, being locked by the back of the block 13^a engaging the farther end of the slot within the ear. The seat, not shown, is designed to be supported upon the bar in any suitable position and can be 20 adjusted thereon longitudinally to suit the rider.

In the operation of the seat-post, it will be obvious that when a sudden shock takes place the bar 24 will move downward describing an arc upon its fulcrum or hinge-pin 25. This movement will cause a compression of the coiled spring 18 and a corresponding expansion of coiled spring 19. The only resistance offered to the load in this 25 instance is the opposition of the coiled spring 18, owing to the fact that as the piston rod 15 moves downward the valve-disk will lift and permit free passage of the oil through the ports and restricted vents. Upon the 30 up-stroke or recoil of the post the piston head, however, will retard the movement. This is accomplished through the valve-disk 16, which closes the ports in the piston head and a partial vacuum between the piston 35 head and bottom 10 of the reservoir is obtained, which vacuum is slowly relieved through the restricted vents 17 and thus the device serves as a shock-absorber in conjunction with the coiled spring 19, which spring

is compressed upon the up-stroke of the 45 seat-post.

By utilizing the hinged bar 24, through which the load is applied to the seat-post, it is obvious that said seat-post can be reciprocated freely without binding and this binding result would attain to the detriment of the movement were the load applied vertically and directly upon said post, which, as shown, is obliquely inclined.

I claim:

1. In a vehicle frame having a horizontally disposed bar, an oblique seat-mast in union with the frame-bar, a spring-controlled sleeve-post in telescopic connection with the seat-mast, and a seat-bar pivotally secured to said frame-bar; the combination of a head extending from the sleeve-post, a pin carried by the head, a bearing-block loosely mounted upon the pin, and a bracket secured to the seat-bar having a depending slotted ear, within which slot the bearing-block is fitted and adapted to have play.

2. In a vehicle frame having a horizontally disposed bar, an oblique seat-mast in union with the frame-bar, a spring-controlled sleeve-post in telescopic connection with the seat-mast, and a seat-bar pivotally secured to said frame-bar; the combination of a head secured to the sleeve-post, ears extending from the head, a pin carried by the ears, a bearing-block loosely mounted upon the pin between the ears, and a bracket secured to the seat-bar having a depending slotted ear, within which slot the bearing-block is fitted and adapted to have play.

In testimony that I claim the foregoing I have hereunto set my hand at Milwaukee in, the county of Milwaukee and State of Wisconsin in the presence of two witnesses.

WILLIAM S. HARLEY.
